BALL POINT PEN CARTRIDGE

Julius M. Kahn, Englewood Cliffs, and Morris Levy,
Bergenfield, N.J., assignors to David Kahn Inc., North
Bergen, N.J., a corporation of New Jersey

Filed Nov. 15, 1963, Ser. No. 77,445

Term of patent 14 years

(Cl. D74—17)

FIG. 1 is a perspective view of the ball point pen cartridge showing our new design;

FIG. 2 is a front elevational view of the cartridge;

FIG. 3 is a side elevational view of the cartridge;

FIG. 4 is a rear elevational view of the cartridge;

FIG. 5 is an elevational view thereof looking at the writing tip end of FIG. 2; and

FIG. 6 is an elevational view looking at the opposite end thereof.

We claim:

The ornamental design for a ball point pen cartridge, substantially as shown and described.
